UNITED STATES PATENT OFFICE.

CHARLES S. BIRD, OF ELYRIA, OHIO.

COMBINED TOBACCO BOX AND CUTTER.

SPECIFICATION forming part of Letters Patent No. 293,404, dated February 12, 1884.
Application filed February 12, 1883. (No model.)

To all whom it may concern:

Be it known that I, CHARLES S. BIRD, of Elyria, in the county of Lorain and State of Ohio, have invented a new and useful Improvement 5 in a Combined Tobacco Box and Cutter, of which the following is a specification.

This invention relates to a pocket tobacco box or receptacle for holding plug-tobacco, provided with a cutting attachment for severing from said plug a small piece sufficient for a chew; and it consists of a box having one open end for holding the plug, and provided with a pivoted frame having a knife shutting across said open end of the box in such a manner that said knife may be used to cut off the required piece from the plug projecting out of said opening, said device being constructed and operating substantially as hereinafter described and claimed.

20 In the accompanying drawings, Figure 1 is a perspective view of my device, showing it closed. Fig. 2 is a like perspective view, showing the knife in the act of cutting, or in position for cutting, a piece off from the projecting plug. Fig. 3 is a longitudinal section of the device.

A represents a rectangular box, having one end left open for the insertion of a plug of tobacco. The interior of said box is provided 30 with a follower-plate, *a*, attached to one end of a spring, *s*, the purpose of which is to push the plug toward the open end of the box.

B designates a frame, the arms *b* of which are pivoted at *b'* to the box A, near its rear or 35 closed end, to give an approximately straight cut to the knife B', which is carried at the op-

posite end of said frame. The knife, when in the position shown in Fig. 1, closes the open end of the box A. The lower front edge of the said frame is made sharp to form a cutting-edge, the front part of the frame forming a knife-blade. The front corner of the frame has a lip, *C*, for the purpose of enabling it to be readily raised.

The manner of using this device is to raise 45 the frame sufficiently to let the plug project as far as required, then close the knife down and sever the piece from the plug by pressing down the frame with the hand.

With the use of this device a tobacco-chewer 50 may easily cut from the plug the required amount for a chew, thus overcoming the difficult and unpleasant operation of biting off the chew.

A damped sponge may be placed in rear 55 of the follower, to keep the tobacco moist.

Having described my invention, I claim—

1. As a new article of manufacture, the tobacco-box herein described, consisting of the body or box A, having an open end, and the 60 frame B, carrying knife B', and pivoted at *b'* to said box A, as set forth.

2. The tobacco-box described, consisting of the box A, having an open end, the frame B, pivoted to the box A at *b'*, the knife B, the 65 closed follower *a*, and spring *s*, as and for the purposes specified.

CHAS. S. BIRD.
